CLAIM

I claim the ornamental design for data processing equipment, as shown and described.

DESCRIPTION

FIG. 1 is a perspective view of data processing equipment of the present invention, shown in an open position;

FIG. 2 is a front side view thereof;

FIG. 3 is a rear side view thereof;

FIG. 4 is a right side view thereof;

FIG. 5 is a left side view thereof;

FIG. 6 is a front view of the present invention, shown in a closed position;

FIG. 7 is a rear view thereof;

FIG. 8 is a left side view thereof;

FIG. 9 is a right side view thereof;

FIG. 10 is a top end view thereof;

FIG. 11 is a bottom end view thereof; and,

FIG. 12 is a perspective view of the present invention, shown in an open position with the dotted lines depicting solely environmental structures and forming no part of the claimed design.
